F. B. MORSE, OF PLANTSVILLE, CONNECTICUT.

Letters Patent No. 94,630, dated September 7, 1869.

IMPROVED DIE FOR FORGING FRENCH CLIPS FOR CARRIAGES.

The Schedule referred to in these Letters Patent and making part of the same.

To all whom it may concern:

Be it known that I, F. B. MORSE, of Plantsville, in the county of Hartford, and State of Connecticut, have invented a new Improvement in Dies for Forging French Clips for Carriages; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view of the upper die inverted.

Figure 2, a perspective view of the lower die.

Figures 3 to 10, inclusive, illustrate the operation of the dies.

Figure 11, a perspective view of the upper first-trimming die, inverted.

Figure 12, a perspective view of the lower first-trimming die.

Figure 13, a perspective view of the upper last-trimming die.

Figure 14, a perspective view of the lower last-trimming die.

This invention relates to an improvement in forging the clip known to the trade as the "French carriage-clip," commonly used on coaches and large carriages.

Heretofore, the clips have been forged by bending, and striking them up into form, in which process it is not only difficult to perfectly form the angles, but when done, the work is not as good as if the forging had been done without bending the metal. By my process, the bending is entirely avoided, and, consequently, a better clip produced; and

The invention consists in a succession of dies, constructed so that the first operation upon the flat or square bar of metal partially forms the clip, then the blanks transferred to succeeding dies, until in the fourth or last the clip is completed.

To enable others skilled in the art to construct and use my invention, I will proceed to describe the same as illustrated in the accompanying drawings.

A is the lower, and B, the upper die-block, the meeting-surfaces wrought the required form, to operate upon the metal in the following manner:

First taking a flat, straight bar of heated metal, it is placed into the first die, a, recesses 1 1, formed in the lower die, and corresponding recesses, 2 2, in the upper die, with a plunger, 3, between each, and a central recess, 4, the metal is struck into the form de-

noted in figs. 3 and 4, the plungers forming the recesses 3 3. Then the blank thus far formed is placed in the second die, b, projections 5 setting into the recesses 3 3 in the blank. In the upper die, two plungers, 6 6, strike upon the blank, upon its edge, and form indentations 7, as seen in figs. 5 and 6.

Then the ends of the blank, from the recesses out, are drawn down, as denoted by broken lines, figs. 5 and 6.

Then the blank is placed into the first-trimming die, fig. 12, so that the recess 3 will lie over the projection 8 in the die, fig. 12.

Then the upper part of the die, with a corresponding recess, 9, strikes down, and cuts out the fin between the two recesses 3 3, so that the blank can be set into the die c, over the bar 10. Then the corresponding die in the upper part strikes down upon the blank, bringing it into the form denoted in figs. 7 and 8.

At this state, there will probably be some surplus metal, forming fins around the edge of the central part of the blank. To trim these from the blank, it is placed into the die, see fig. 14, and the follower, fig. 13, dropped thereon, and the blank trimmed.

Then the blank is placed into the fourth die, d, the bar 10 at that point being of the proper form and size for the inner angle of the clip, and the upper die of the desired form for the outside of the clip, and the upper die being struck upon the blank in the lower die, forms and finishes the clip; but during the operation of finishing by the dies, it is at times necessary to trim the fin or surplus metal from the clip, which is done by the dies, figs. 13 and 14.

Thus I construct a clip without bending the metal, so that no part of the metal is overstrained, but, on the contrary, is consolidated so as to be much stronger and finer than in the ordinary process for making such clips.

Having, therefore, thus fully described my invention, What I claim as new and useful, and desire to secure by Letters Patent, is—

The die for forging "French carriage-clips," constructed substantially as described, so as to forge the clip without bending.

F. B. MORSE.
